United States Patent Office

Des. 182,801
Patented May 20, 1958

182,801

FOOT REST

Nathan Garshof, Los Angeles, Calif.

Application July 26, 1957, Serial No. 47,097

Term of patent 7 years

(Cl. D15—8)

I claim:

The ornamental design for a foot rest, as shown and described.
